UNITED STATES PATENT OFFICE.

EDGAR F. ROBERTS, OF DETROIT, MICHIGAN.

METHOD OF CONSTRUCTING BUILDINGS.

Application filed December 4, 1920. Serial No. 428,311.

To all whom it may concern:

Be it known that I, EDGAR F. ROBERTS, a citizen of the United States of America, residing at Detroit, in the county of Wayne and State of Michigan, have invented certain new and useful Improvements in Methods of Constructing Buildings, of which the following is a specification, reference being had therein to the accompanying drawings.

10 This invention relates to a process of constructing buildings. It has for an object the utilization of raw materials with the least possible transportation and manipulation. Another object of my invention is to produce a building which shall be fire-proof, 15 water-proof and permanent.

I accomplish these and other objects by molding the walls, partitions, floors, roof and other parts of a house of plastic clay, 20 drying the clay while held in position and then burning the molded material. After a rough wall has been constructed by this process the interior and exterior surfaces may be given any desired covering or decoration or in certain cases a surface may be 25 prepared at the time the clay is molded which will be baked in place and serve as the permanent surface.

In the drawings, 30 Figure 1 is a diagrammatic vertical section of a building showing the molds in place ready for the drying operation;

Fig. 2 is a horizontal section, each quarter of which represents a different arrangement 35 of a plastic material;

Figs. 3 and 4 are an elevation and section respectively of another form of mold;

Fig. 5 is a section of a fragment of a wall 40 showing a preferred form of mold by which a hollow wall may be constructed;

Fig. 6 is a vertical section on the line VIII—VIII of Fig. 5;

Figs. 7, 8 and 9 are sections illustrating 45 various ways in which the outer surface of the walls of the building may be finished; and

Fig. 10 is a section of a heat insulating casing.

Clays and shales are so widely distributed 50 that their use as building materials in the form of bricks, tiles and terra cotta is almost universal. The present practice is to prepare these materials in pieces of a size and weight suitable for easy handling and 55 transportation and burn them in kilns lo-

cated near the clay pits. In the process of manufacture each piece is handled several times. It must then be transported to the place where a building is to be erected and set in place by workmen using some kind 60 of cement or mortar to hold it in position. Each handling of the material requires time and since each piece may be handled many times, a considerable part of the expense of building a wall is due to the mere handling 65 of the material.

In many places where the excavation is made for a basement, a considerable amount of clay must be hauled away, in many cases to a considerable distance, because clay is 70 not desirable as a surface material for a garden.

I propose to use clay or shale in places where it forms the material underlying the surface, by molding it into structural shapes 75 by the use of suitable molds and machinery and, after drying it thoroughly, the molded clay will be burnt in position so that the completed house will consist of a ceramic structure burnt in place.

Where the materials in the location selected for the house are suitable, they may be used for the exterior and the surface of the walls may be made to assume any desired configuration by using the ordinary 85 methods employed today in terra cotta work. If the clays in the location are not of a quality to produce a good effect, the surface or the entire structure may consist of other suitable clays brought from a distance.

In many cases, instead of making the surface in a single piece with the body of the wall, the first operation will be to construct a rough wall which will act merely as a 95 support and apply to this rough wall a surface layer of plaster, stucco, tile, brick, stone, marble, mosaic, terazzo, cement, metal, wood or any other suitable or desired material.

The walls may be made solid but preferably would be made with vertical open passages as indicated in Figs. 2, 5 and 6, the structure being similar to that used in the ordinary hollow building tile. In the lower walls, the partitions in the bottom wall will 105 be as numerous as required to give the necessary structural strength, while in the upper walls the partition portions may be omitted.

The preparation of the clay or shale by 110

crushing and mixing with water into a plastic mass will be conducted as is customary in the manufacture of brick or tile and the plastic mass will be squeezed into place in 5 suitable molds arranged where the wall is to remain. I have shown a preferred form of mold in Figs. 5 and 6 in which a rough wooden framework consisting of horizontal pieces 1 secured to vertical strips 2, forms 10 the support for a plaster of Paris facing 3. Vertical channels or spaces 4 are left between the plaster and the wooden support and these are conveniently formed by securing a metallic fabric 5 or expanded metal 15 lath to the wooden support 1 in a series of outwardly bent curves. A mold facing such as has been described is used for the inner and outer surfaces of a wall or partition, the hollow spaces in the wall being formed 20 by the use of hollow plaster of Paris tubes 6. These tubes are reinforced and the central tubular opening maintained by a wire mesh or expanded metal member 7. As shown in Fig. 4, the spaces in the wall are rectangular and the cross partitions between the 25 spaces are staggered. As shown in the lower left hand corner of Fig. 2, there may be but a single row of openings between the outer and inner surface of the wall. In the 30 lower right hand corner of Fig. 2, the partitions between the outer and inner faces of the wall are shown as inclined at an angle of about 60° to each face, the open spaces being triangular. It will be obvious that 35 these vertical passages may be of any shape and that the arrangement of the partitions between the inner and outer surface of the wall may be varied according to the circumstances of the case.

40 When the wet clay is forced into the spaces between the mold members, the moisture in the clay passes out into the plaster of Paris mold facings and by creating currents of air through the open passages in 45 the tubes 6 and through the passages 4 in the outer mold faces, the drying out of the thin layers of clay will be accomplished uniformly and rapidly. When the clay has dried sufficiently to hold its own weight, the 50 tubes 6 may be removed by pulling them upward. As shown in Fig. 6, they are larger at the top than at the bottom, this tapering structure permitting their ready withdrawal. Supporting loops 8 secured in the 55 upper portions of the molds, serve as a means by which the tubes may be lifted.

After the molds have been withdrawn, suitable supporting means may be placed 60 against the inner and outer faces of the walls as shown in Figs. 1 and 2. In Figs. 1 and 2, these supporting members 9 are shown as provided with electric heating elements 10 by which the preliminary drying may be hastened and by which the burning of the 65 tile may be accomplished, in cases where

electric current is available and where the cost is not excessive. These supporting members 9 will have a metallic face 11 in contact with the plastic material and some form of heat insulating material 12 outside 70 of the heating elements 10.

Ordinarily, however, the burning of the tile as well as the preliminary drying will be more cheaply accomplished by the use of 75 fuel oil.

A modified form of supporting member is shown in Figs. 3 and 4 in which steam coils 18 are arranged between an inner metallic face 19 and an outer metallic face 20. A suitable insulating layer 21 is used 80 to prevent loss of heat.

If the size and weight of the walls are not excessive and if the supporting structures can be made to hold the plastic clay in position, the entire structure may be 85 burnt at a single operation. It is probable however, that it will be necessary to mold, dry and burn the various sections singly to avoid distortion of the plastic material by strains which it will not have strength 90 enough to resist until after being burnt.

It will be obvious that substantially all of the expedients now used in reinforced concrete building may be adapted to this ceramic structure by easy modifications. Since 95 common bricks are rarely fired above 1050° C. and face brick rarely above 1250° C. reinforcements of steel or cast iron may be used wherever desired, since the melting point of steel and cast iron is higher than the 100 temperature to which the plastic material need be raised while it is being hard burned.

All passages, as for ventilation, for heating systems, for vacuum cleaner pipes, and for electric wires, or for any other purpose, 105 may be provided while the walls or partitions are being molded. Door and window openings will of course be left and stairways, floors and roofs will be molded and provided with proper reinforcements. I 110 contemplate the formation of baths, lavatories, kitchen sinks, refrigerating chambers, ovens, fireless cooker chambers, medicine cabinets, shelves, laundry tubs, fire places, and many other structural parts during the plastic operations, and previously 115 molded ceramic structures whether previously burnt or not may be installed in position during the plastic operations.

As suggested, the surfaces may receive 120 any desired finish. In Fig. 7 the outer section 22 of the rough burnt clay wall has recesses 23 at intervals with which a coating of stucco 24 may engage. The stucco may have any ornamental material 125 pressed into the surface while it is plastic as is well known in the art. Instead of the stucco or in connection therewith, a surface layer of tiles 26 may be used, secured to the rough wall by any suitable cement or mor- 130

tar 27. Another surface finish is indicated in Fig. 8, in which the portion of the wall above the water-table 28, is faced with brick 29, and a portion below the water-table, is surfaced with stone or concrete blocks 30.

In certain instances, I may apply to the surface of the dried wall 22 before it has been burnt a thin layer of clay or a clayey mixture of a quality such as to give a pleasing appearance when it has been burnt. This surface may be scored to imitate brick or tile as indicated at 31.

It may be found better to burn the rough wall first and then apply the clay surface which will subsequently be burnt.

Suitable glazes may be applied to any surfaces, and by controlling the composition of the ceramic materials and by regulating the temperature, any desired degree of vitrification may be obtained.

After the structural elements are thoroughly dried, if they have sufficient strength to sustain the weight upon them, the molds will be removed and heat insulating members 32 of any suitable construction will be placed on both sides but not in contact with the dried clay, so that the flames and heat from the oil burners 13 may reach both the outer and inner surfaces as well as the hollow interior. Where possible, the entire building will be enclosed in a single insulating casing so that the entire burning may be accomplished at a single operation to conserve fuel.

The specific structures herein shown are to be understood as merely illustrative, since obviously many changes in detail may be made without departing from the spirit of my invention.

I therefore wish the following claims to be construed broadly as covering any means of producing the desired configuration of the structural elements, and any plastic materials capable of being converted into a strong and resistant substance by the application of a high temperature.

I claim:

1. A process of constructing a building which consists in forming a wall in situ and of plastic clay with continuous vertical passages, providing spaced closures about said wall, and burning said wall by means of application of heat applied at the bottom of said vertical passages and between said closures and the outer surface of said wall.

2. A process according to claim 1, wherein the building is provided with a roof wherein in the passages are extended within and around the said roof.

3. A method of constructing a building which consists in forming a plastic wall about molds of porous material and adapted to form continuous vertical passages in said wall, and further, exterior molds of porous material arranged within end closures spaced thereby from the exterior of said wall, removing said porous molds after they have absorbed moisture from said plastic wall, and burning said wall by means of heat directed upwardly through said vertical passages and to the spaces between said end closures and said wall.

In testimony whereof I affix my signature in presence of two witnesses.

EDGAR F. ROBERTS.
